UNITED STATES PATENT OFFICE.

ARCHER LE ROY BOLTON, OF NORTH ANDOVER, MASSACHUSETTS, ASSIGNEE TO JOHN W. BOLTON AND SONS, INC., OF LAWRENCE, MASSACHUSETTS, A CORPORATION OF MASSACHUSETTS.

SELF-SUPPORTING LINING FOR JORDAN-ENGINE SHELLS.

Application filed October 12, 1925. Serial No. 61,873.

This invention relates to paper making machinery, and particularly to the shells of what are known as Jordan engines. A Jordan engine comprises a frustro-conical plug 5 having bars on its surface which revolves inside of a shell of frustro-conical shape, from the inside of which project knives which cooperate with the bars on the plug.

The knives and the wooden separators, or 10 woods by which they are separated, wear out more rapidly than the fixed or permanent shell, and it is necessary from time to time to replace them in the shell.

Usually the removing of the old knives 15 and separators, and replacing of new ones is done at the paper mill, or the shell is removed and shipped to a machine shop where the replacement is made. In either case the Jordan engine is out of operation during 20 that period.

As usually made, the knives are bent at an angle, and their cross section is rectangular, that is the top and bottom walls are parallel and the side walls are parallel. On 25 the other hand the separators are made so that in cross section they resemble a key-stone.

As usually inserted the knives and separators are alternately placed, and at intervals wooden wedges are driven in between 30 two separators which have flat faces substantially parallel so as to bind the whole built up filling in place. As the knives have parallel faces however they are kept in position only by friction of the separators which swell when they come in contact with the wet paper stock.

However there is danger that the knives will slip inward, and to avoid this, various 40 expedients have been tried.

Abbe in his Patents No. 247,286, Sept. 20, 1881, and 238,545, March 8, 1881 proposes to string knives and separators on curved rods or wires on which are nuts, whereby they 45 can be forced together, while Martindale in his Patent No. 1,494,265, of May 13, 1924, proposes to make coinciding notches in the separators and knives, and to fill these with Babbitt metal, or to pass through a wire and 50 fill in with babbitt, thus holding the parts

rigidly in position so that the whole filling can be bodily transported in the same manner that is indicated by Bahr in his Patent No. 1,133,215, of Mar. 23, 1915, who uses a one-piece integral filling.

Martindale's knives and separators cannot move laterally.

A filling built up of metal knives, alternating with wooden separators or woods, has many advantages, among which are the facts 60 that it is lighter and more elastic.

This invention comprises the manner of holding the knives and separators in a segment of a Jordan engine shell, the method consisting of their intersupporting or interlocking so that no individual knife or separator can slip inward, being held by whatever is on each side, either separator or knife, and cannot slip outward on account of the shell itself.

My preferred type of construction includes a bodily transportable thin metal lining shell in which knives and separators have been placed, and which hold each other, as indicated in the last paragraph, from moving inward, and being prevented from moving outward by the thin metal shell.

It is an improvement on my application for patent on "Removable lining shell for Jordan engines" filed June 29, 1922, Serial No. 571,720, pending herewith.

My knives and separators can be tightened and moved laterally with reference to the shell if the wood shrinks, and can therefore be forced together circumferentially by 85 wedges as much as desired.

In the drawings, Fig. 1 is a vertical longitudinal section of a Jordan engine shell with one of my bodily removable sections fastened in position.

Fig. 2 is a view from the left of Fig. 1 or from the large end of a Jordan engine shell with one of my sections in place.

Fig. 3 is a detail showing the split part of one of my bodily removable sections before the wedge is inserted.

Fig. 4 shows a wedge partly driven in.

Fig. 5 is an elevation of one starting bar.

Fig. 6 is an elevation of another starting

bar.

Fig. 7 is a plan view of the fastening bar. Fig. 8 is a section on line 8—8 of Fig. 7.

Fig. 9 is a detail end elevation showing my preferred form of filling as it is held together while being shipped.

Fig. 10 is a view from the inside of part of Fig. 9.

Fig. 11 is a sectional detail showing a modified form of knives and separators.

10 Figs. 12, 13, 14 are vertical sectional views showing other forms of knives and separators.

Fig. 15 is an elevation from the large end of a thin metal case which is not split and 15 which has no starting bars.

Fig. 16 is a vertical sectional detail showing how I may use knives and separators without wedges.

Fig. 17 is an end elevation of Fig. 16.

20 Fig. 18 is an end elevation showing how my knives and separators can be built up in a shell of the split type without wedges.

Figs. 19 and 20 are elevations showing 25 different types of thin metal shells which I might use.

In the drawings, G represents the fixed or permanent shell of a Jordan engine having the small end 10 and the large end 11. Inside this revolves the plug which is not 30 shown.

In my preferred construction, I use three lining shells B¹, B², B³, which are substantially alike.

Each includes a frustro-conical section of 35 tough thin metal 20 split lengthwise so that there are two parallel, or substantially parallel straight edges 21 and 22 which adjoin each other, the shell 20 being of such size that it will fit inside of the fixed shell G, 40 either as first, second or third section when the straight edges 21 and 22 are a short distance or are far enough apart to permit the insertion of a fitting wedge L.

As shown, the metal at each straight edge 45 is bent inward at 23 and 24, and may also be bent around on the front and back edge at 25 and 26.

Preferably the metal at the large end 28 is bent around inward so that at the straight 50 edges and the large curved edge a metal rim extends inward.

At certain spaced positions, the metal rim at the large end can be bent down as at 29, for a purpose to be described.

55 If this thin metal is stiff enough, I can start building knives and separators from the straight edges 23 and 24, using them as starting members, but I prefer to use heavier metal starting bars D and E attached to the

60 thin metal as by means of rivets 30 and 31. Each of these starting bars is preferably of skeleton construction to combine lightness and strength. In each is a radial hole such as 32 and 33.

65 To hold the segment 20 together in ship-

ping I may use two or more links such as F through holes 71 and 72, in which pass the bolts 70 into the holes 32 and 33.

To fasten the filling such as B¹, B², B³, to the fixed shell G I might pass screws such as C directly through slots such as 61 in the shell 20, but I prefer to use a metal separator bar 60 which may be positioned between two or more knives H, preferably about opposite to the split part of the shell. This fastener bar preferably is of angular shape 75 conforming to the adjoining knives and is of skeleton form, having the slots 62 enlarged at 63, whereby the heads of the fastening screws or bolts C will be countersunk 80 below the surface of the separator and the shank will pass through the slots 61 and 62 into suitable screw holes such as 64 in the fixed shell G.

This fastener bolt C keeps the filling shell 85 from turning, and when a fitting wedge L is driven in between the two straight edges, the filling shell is accurately and firmly fixed in position.

In my preferred construction, each knife 90 H has parallel sides and near the bottom of each side, ribs 40, 40, while each of the ordinary wooden separators K, is smaller on the inside than the outside, being of substantially keystone cross section, and has on each side a groove 50 which registers with a rib 40, on an adjoining knife.

Preferably at intervals of perhaps 60° I provide separators such as 53 shown in Figs. 9 and 10, which have one side bent and the other side 55 straight. On each side is a groove 56 or 57. Resting against each straight face 55 is a shallow straight metal strip 150 like a knife, having a rib 151 which enters a groove 57 and another rib 152 on its 100 opposite side. Between these two separating members 150, 150, I drive a tightening wedge such as A having on each side a groove 58 105 which fits a rib 152. The adjoining members throughout thus hold each other in place positively and not merely by friction. When the wedge A is entirely driven in, the part 29 can be bent back over its end to prevent the wedge from coming out.

In building my filling, I preferably place 110 the thin metal case 20, with its axis vertical in a suitable form, which is of the size of the fixed shell G into which it is to go, and starting at either starting bar D or E, I place side by side a knife and a separator, pressing 115 them firmly together, and at appropriate intervals, place the special separators 53, 53, and between these insert the small end of a tightening wedge A.

I continue this process around as far as 120 the fastening bar 60, if one is used, or I may build in both directions.

When the whole case is suitably filled I drive in the wedges A as far as they will go, and bend over the parts 29, or I may leave 125

them projecting while they are being shipped so that in case the wooden separators dry to any extent they may be driven in slightly to keep the organization tight.

5 Before taking it out of the form, I put in place links such as F, and when this is done the whole organization can be bodily transported to any point desired.

In Fig. 12, I show my interlocking or intersupporting method applied to a fixed shell such as P. In this case I may use only one starting bar, which may be a rib 80, integral with P, and of course no fastener such as C is necessary, and I may use only one wedge 15 such as 81 which tightens the knives and separators in place.

In this view, I show the knives 82 and the separators 83 as having no ribs nor grooves, nor other projections, but the knives as well 20 as the separators made of keystone shape whereby they are intersupporting, if not interlocking.

In Fig. 11, I show knives such as 90, each with a groove 91 instead of a rib, while each 25 separator 92 has a rib 93 instead of a groove.

In Fig. 13, I show in each knife 95, and each wood 96, a groove such as 97 or 98, in which an independent key 99 fits.

In Fig. 14, I show woods 100 with plane 30 faces while each knife 101 is provided with points such as 102, which when the wedges are driven in, are forced into the separators, thus interlocking and supporting them in place.

35 In Fig. 15, I show a shell 120 which may be of thin metal or of heavy metal or which might be the permanent shell of the engine. It is of the usual frustro-conical form and in it are built up knives 123 which have on 40 each side ribs 124 and the separators 121 with grooves 122.

In this construction the shell is not split and there is no starting bar used, but a 45 tightening wedge 125 is shown as used. If this is applied to a detachable lining shell, it may be held in place by a screw 126.

As shown in Figs. 16 and 17, I may use a 50 larger number of shorter removable sections 130 and 131 each made of thin metal and each having assembled in it, knives 133 between which are separators 132 the knives having ribs 136 and the separators grooves 137 which interlock and each of which is straight on the edge, instead of being bent.

55 With this construction, separators which are made entirely of metal can be used and can be driven into position from the large end without the use of starting bars or wedges. When two sections such as 135, extending at a different angle from knives 133, 133, are placed together, end to end, the same 60 result is obtained as where each knife in a longer section is bent.

In Fig. 18, I show a thin metal shell 140 65 which is split and then spread out as shown

by the full line position. While in this position, the knives 141 having ribs 143, and the separators 142, with grooves 144 are placed alternately side by side and when all are placed, shell 140 is bent up to the circular 70 position shown by the dotted lines. This forces the ribs into the grooves and holds the whole construction together.

In Fig. 19, the knives 151 and separators 152 are held together by a relatively thin 75 metal band 153 to form a section 150.

In Fig. 20, the knives 158 and separators 159 are held together by two bands of thin metal 156 and 157, one near each end thereby forming a bodily movable section 155. 80

I claim:

1. The combination in a bodily removable lining for Jordan engine shells of a thin metal segmental section having its straight edges bent inward, its smaller curved edge 85 not bent but its larger curved edge bent inward except at a wedge position; with a plurality of wooden separators of keystone shape positioned around the inside of the thin metal section, each separator having on 90 each side a groove; a plurality of knives each positioned between two separators, and each having on each side a rib which enters the groove in a separator; and a tightening wedge located between two separators 95 in line with a wedge position at the large end.

2. The combination in a bodily removable lining for Jordan engine shells of a thin metal segmental section having straight 100 edges, its smaller curved edge not bent but its larger curved edge bent inward, and having starting bars fixed to its straight edges; with a plurality of wooden separators of keystone shape positioned around the inside of the thin metal section, each separator 105 having on each side a groove; a plurality of knives each positioned between two separators, and each having on each side a rib which enters the groove in a separator; and a tightening wedge located between two 110 separators.

3. The combination in a bodily removable lining for Jordan engine shells of a thin metal segmental section having straight 115 edges with starting bars fixed thereto; with a plurality of wooden separators positioned around the inside of the thin metal section, each separator having on each side a groove; a plurality of knives each positioned between 120 two separators, and each having on each side a rib which enters the groove in a separator; and a tightening wedge located between two separators.

4. Means constituting a pre-constructed 125 unitary device adapted to be inserted and expanded within the shell of a pulping engine and operating as a filler or lining therefor, said device comprising a series of interlocking metal knives and separators ar- 130

1. ranged in alternating relation; means to force them together; means to keep them held together; means peripherally applied to prevent them from moving radially outward; and a wedge adapted to be inserted in the longitudinal opening formed by the split in said frusto-conical unit and operable to expand it radially when placed in operative position within the casing of the engine.
2. 5. Means constituting a pre-constructed filler or lining for pulping engines, adapted to be inserted, expanded, and fixedly maintained within the shell of the engine, consisting of a plurality of frusto-conical split units, of varying radial dimensions adapted to register end to end and form a single unit of uniform frusto-conical form, when assembled in series arrangement within the shell of the engine, each of said units comprising a series of interlocking metal knives and separators, arranged in alternating relation; means peripherally applied to prevent the knives and separators from moving radially; means attached to the ends of the last named means to limit their lateral movement; means to force them together into interlocking relation; a wedge adapted to be inserted between the adjacent edges of said split and operable to expand said unit radially and simultaneously effect an unbroken periphery thereon when placed in operative position within the casing of the engine; and means to secure the series of units to the inside of the shell of the engine.
3. 6. The combination with the permanent shell of a Jordan engine; of a thin metal segmental section having adjoining straight edges; a starting bar fixed at each of said straight edges; a fastener by which the thin metal section is attached to the permanent shell; a plurality of keystone shaped separators arranged inside said thin metal section; a plurality of knives each positioned between two separators, the separators and knives having interlocking parts between them; a tightening wedge; and a fitting wedge positioned between the starting bars.
4. 7. The combination in a bodily removable lining for Jordan engine shells of a thin metal segmental section having adjoining straight edges; a starting bar fixed along each of said straight edges; a plurality of keystone shaped separators arranged inside said thin metal section; a plurality of knives each positioned between two separators, the separators and knives having interlocking parts between them; and a tightening wedge.
5. 8. The combination with the frusto-conical shell of a Jordan engine; of a starting bar fixed inside thereof; a plurality of separators arranged around the inside of the shell; a plurality of knives each positioned between two separators, the separators and knives having interlocking parts between them; means to laterally force the knives and separators together and against the starting bar and to keep them together.
6. 9. The combination with the permanent shell of a Jordan engine; of a thin metal segmental section having adjoining straight edges; a starting bar fixed at each of said straight edges; a fastener by which the thin metal section is attached to the permanent shell; a plurality of interlocking knives and wood separators alternately positioned around the inside of the thin metal section; tightening wedges; and a fitting wedge positioned between the starting bars.
7. 10. The combination in a bodily removable lining for Jordan engine shells of a thin metal segmental section having adjoining straight edges; a starting bar fixed along each of said straight edges; a plurality of substantially alternately disposed interlocking knives and wood separators; and one or more tightening wedges.
8. 11. In a Jordan engine, the combination with a frusto-conical metal shell having a longitudinal starting bar fixed thereto; of a plurality of intersupporting knives and wood separators positioned around the inside of the shell and adjoining the starting bar.
9. 12. In a Jordan engine, the combination with a frusto-conical metal shell; of a plurality of interlocking knives and separators positioned around the inside of the shell.
10. 13. In a Jordan engine, the combination with a frusto-conical metal shell; of a plurality of interlocking knives, separators, wedges, and starting bars positioned around the inside of the shell.
11. 14. In a Jordan engine, the combination with a frusto-conical metal shell; of a plurality of knives, separators, wedges and starting bars positioned around the inside of the shell and each member being of such cross section that it cannot move inward without moving with it both adjoining members.
12. 15. In a Jordan engine, the combination with a frusto-conical metal shell; of a plurality of knives and members which serve to separate them, each knife and member being of such cross section that it cannot move inward without moving with it both adjoining members or knives or the adjoining member and knife.
13. 16. The combination in a bodily removable lining for Jordan engine shells of a thin metal segmental section; with a plurality of knives and members which serve to separate them, each knife and member being of such cross section that it cannot move inward without moving with it both adjoining members or knives, or the adjoining member and knife, but which can be moved circumferentially; one of said members being a wedge for tightening the knives and members against each other.

17. The combination in a bodily removable lining for Jordan engine shells of a plurality of knives and members which serve to separate them, each knife and member being of such cross section that it cannot move inward without moving with it both adjoining members or knives, or the adjoining member or knife, but which can be moved circumferentially; with means to prevent said

10 knives and members from moving outward.

18. The combination in a bodily removable lining for Jordan engine shells of a plurality of knives and members which serve to separate them, each knife and member being of such form that it cannot move inward without moving with it both adjoining members or knives, or the adjoining member or knife, with means to prevent said knives and members from moving outward.

15 ARCHER LE ROY BOLTON.
